CLAIM

The ornamental design for a lip balm applicator, as shown and described.

DESCRIPTION

FIG. 1 is a front view of the applicator, showing my new design, the rear view of the cylindrical portion being the same as the side shown.

FIG. 2 is a top view thereof.

FIG. 3 is a side view of the cap element of the design seen in the direction of arrow 3 in FIG. 2; and shown separately for ease of illustration.

FIG. 4 is a bottom view of FIG. 1; and,

FIG. 5 is a bottom view of FIG. 3.

The surface(s) or portion(s) of the article not shown in the drawing or described in the specification form(s) no part of the claimed design.
